UNITED STATES PATENT OFFICE.

HUGH C. DAVEY, OF SAN JOSE, CALIFORNIA.

ROTARY FURNACE.

SPECIFICATION forming part of Letters Patent No. 779,119, dated January 3, 1905.

Application filed February 9, 1904. Serial No. 192,810.

To all whom it may concern:

Be it known that I, HUGH C. DAVEY, a citizen of the United States, residing at San Jose, in the county of Santa Clara and State of California, have invented new and useful Improvements in Rotary Furnaces, of which the following is a specification.

My invention relates to improvements in roasting-furnaces of that class in which a horizontal or slightly - inclined cylinder is revolved upon its axis and the heat of the furnace is applied, the ore being caused to pass gradually from one end to the other.

My invention consists in the combination of a plurality of revoluble inclined barrels, each having stationary heads and furnaces connecting therewith, through which heat is delivered to pass through the barrels. These barrels are set with relation to each other and provided with intermediate automatic discharge-chutes from the end of one cylinder and receivers into which the ore passes and by which it is delivered to the succeeding cylinder.

My invention also comprises details of construction, which will be more fully explained by reference to the accompanying drawings, in which—

Figure 1 is a longitudinal section of one cylinder and connections. Fig. 2 is an end view of same with connections and partial section of following cylinder.

As shown in the drawings, A is a suitable bed or framework, having mounted upon it the journaled bearing - rollers 2, which are fixed upon shafts journaled at each side of the center of the frame. Upon these rollers the cylinder 3 is mounted, this cylinder having a surrounding band or track, as at 4, corresponding with each pair of rollers 2, so that as it rests upon these rollers it will also be revolved by their revolution. At the receiving end of the cylinder is formed an outwardly-tapering conical head, as at 5, which is fixed to and revoluble with the cylinder. The cone-shaped projection is of some smaller diameter than the interior of the cylinder, and the latter is suitably lined with fire-brick or an equivalent heat resistant. The projecting cone at the

head of each cylinder extends through brick 50 or masonry work, within which it fits sufficiently closely, and the ore to be roasted is fed into this end from a suitable chute or source of supply. At the opposite end the cylinder has a section of larger diameter, as at 6, and 55 the flange 7 at the end of this section is revoluble within a circular channel, as at 8, formed in the head 9. This head is stationary and suitably mounted and has at the lower part an inclined chute, as at 10, so that as the ore 60 travels gradually from one end of the cylinder to the other by reason of its inclination, or by the assistance of spirally-disposed ribs if it is desired to use such devices, the ore will pass into the head 9, thence out through 65 the chute 10. This chute discharges into a hopper or receiver, as at 11, and from the bottom of this receiver a chute 12 extends into the conical head or cap 5 of the succeeding roasting-cylinder.

Each succeeding cylinder is mounted similarly to the one previously described, at any desired relation therewith and sufficiently lower than the preceding one, so that the ore may be automatically delivered from one cylinder to the next succeeding one.

13 represents a furnace or fireplace, of which one is located at the discharge end of each of the cylinders, and the furnaces have open communication with the stationary heads 9; 80 so that when the fire is made the products of combustion are delivered from the furnace through the head into the enlargement 6 and thence pass through the body of the furnace, the revolution of which causes the ore to be 85 continually turned and fresh portions brought into contact with the hot products passing through the cylinder. In this manner the ore is gradually roasted, passing through as many connected furnaces as may be found desirable 90 to complete the operation.

As the cylinders usually have their axes inclined in the direction of their length, it is necessary to provide some means for preventing the cylinders from moving lengthwise during 95 their revolutions. I have here shown such a means in the form of bevel - faced annular rings 15, carried by the cylinders and contact-

ing with corresponding beveled wheels or pulleys 15', turning upon fixed axes and serving as thrust-bearings.

This furnace is especially designed for de-
5 sulfurizing ore—such as, for example, ores con-
taining quicksilver or other valuable metals.

Furnaces of comparatively small capacity
are usually employed, because if long cham-
bers are used with single fires too intense a
10 heat must be applied at the fireplace end in
order to be effective through the whole fur-
nace, and this melts and slags the ore, so that
it will not pass freely.

This invention is designed to use independ-
15 ent furnaces of comparatively short length
with separate fires, each serving to heat its
own cylinder, and the partially-roasted ore
may be successively delivered in a heated con-
dition to the following cylinder and subjected
20 to therein to comparatively low heat, which while
being sufficient to roast the ore and expel the
sulfur will not cause it to melt or slag. These
separate furnaces may be mounted in any suit-
able or convenient relation with each other and
25 may be connected with independent chimneys
or escape-flues.

Having thus described my invention, what
I claim, and desire to secure by Letters Pat-
ent, is—

30 1. An improved ore-roasting apparatus hav-
ing in combination a plurality of inclined revo-
luble cylinders, each having a conical receiv-
ing end forming substantially a close joint
through the masonry in which it is turnable,
35 an enlarged head rigid with the discharge end
of the revolute cylinder said head having an
outwardly-extending annular flange, a station-
ary head abutting the head of the cylinder and
having an annular channel interior to one end
40 to receive said flange, a furnace proximate to

the stationary head and delivering the prod-
ucts of combustion thereinto and into the cyl-
inder, said stationary head having a delivery-
chute, and an open uninclosed receiver in com-
munication with the said chute and interposed
45 between the same and the conical inlet of the
succeeding cylinder.

2. An improved ore-roasting apparatus hav-
ing in combination a plurality of inclined revo-
luble cylinders each having a conical receiv-
ing end forming substantially a close joint
through the masonry in which it is turnable,
50 an enlarged head fixed to the discharge end of
the cylinder, open at both ends and having a
projecting flange surrounding the outer end, 55
a stationary head abutting the outer end of
the first-named head and open at both ends,
and having an annular channel around the in-
terior of the inner end to receive said sur-
rounding flange, said stationary head having
60 a chute extension at its lower end, a furnace
communicating with the opening in the outer
end of the stationary head and delivering the
products of combustion thereto and to the ore,
an open uninclosed receiver between the chute
65 of the stationary head and conical inlet of the
succeeding cylinder, and thrust-bearings to
maintain the joint between the conical inlet
and the masonry said bearings consisting of
70 annular beveled rings on the cylinder and cor-
responding beveled pinions journaled at right
angles with the cylinder-axis.

In testimony whereof I have hereunto set
my hand in presence of two subscribing wit-
nesses.

HUGH C. DAVEY.
